Dec. 1224

Theodore W. Gillagore of Philadelphia, Pa.

Assignor to Savery & Co. of same place.

Letters Patent No. 1224, dated April 3, 1860.

The Schedule referred to in these Letters Patent and making part of the same.

To all whom it may concern:

Be it known that I, Theodore W. Gillagore, of the City of Philadelphia, in the State of Pennsylvania, have invented or produced a new and original design for fire-dogs, and I do hereby declare that the following is a full, and exact description of the same, reference being had to the annexed drawings, making a part of this specification, and to the letters of reference marked theron.

For the purpose of nominal distinction, I call this design for a fire-dog "The Urn Pattern". It consists of a shield and ornamented scrolls, surmounted by an urn, and connected together so as to produce the general form and outline shown in the drawing, to be cast of metal to serve as the front of a fire-dog, A. A. being the legs; B. the shield; C. C. the body; D. the neck, and E. the urn.

Des. 1224

The legs (1, A,) are ornamented with the foliage 1-1. The body scrolls (6, C,) are ornamented with the shell work 2-2; the shield (B,) with the foliage 4-4; and the neck (D) with the foliage 3-3, as shown in the drawing. The urn E, surrounds the whole.

What I claim as my invention or production and desire to secure by Letters Patent is -

The configuration and ornamentations herein described and set forth, as a new and original design for fire-dogs.
